UNITED STATES PATENT OFFICE.

FREDERICK WILLIAM CHAPPELL, OF PONTARDawe, SWANSEA VALLEY, WALES.

LAST FOR BOOTS, SHOES, AND THE LIKE.

Application filed March 10, 1924. Serial No. 698,253.

To all whom it may concern:

Be it known that I, FREDERICK WILLIAM CHAPPELL, of 22 Tawe Terrace, Pontardawe, Swansea Valley, in the county of Glamorgan, Wales, Great Britain, a subject of the King of Great Britain and Ireland, have invented an Improved Last for Boots, Shoes, and the like (for which I have filed application in Great Britain, No. 9548, filed the 10 26th March, 1923), of which the following is a specification.

This invention relates to an improved last for boots, shoes and the like and has for its objects to avoid the necessity for the 15 repairer having a large number of different sized lasts to fit the various sizes of boots and shoes which he has to repair, as is requisite at present, and to provide an inexpensive construction and one in which the 20 change of size to suit different boots or shoes or the like can be quickly and easily effected.

According to the invention I provide a 25 number of flat last plates, each in the shape of the sole and heel of the foot, and of varying sizes according to the boot, shoe or the like which has to be repaired, and I provide means for detachably connecting any number of them to a base piece which 30 is mounted upon a single strong pillar and consists preferably of a miniature foot cast integral with the pillar or connected therewith. The last plates preferably interlock with each other, and one of the plates also 35 interlocks with the base piece. The means for securing any number of last plates to the base piece preferably consists of a bolt and wing nut, the head of the bolt engaging in the securing position in a recess in 40 the (at the time) outermost last plate, but being adapted when turned through an angle to slip completely through a slot in the last plate, so as to permit the latter to be removed. The recesses and slots described are of course provided in all the 45 last plates.

In connection with the foregoing I may say that sets of interlocking last plates are known in which the separate toe portions 50 are secured by a screw to one pillar, while the separate heel portions are secured by similar means to an adjacent pillar. In this case the heel and toe portions have to be adjusted or removed separately and a screw 55 driver is necessary to remove the screws. In the present invention the last plates can be

removed or replaced without any special instrument and without even removing the securing means from the last.

The invention will now be more fully described by way of example with reference to the accompanying drawings in which—

Fig. 1 is a side elevation of the complete last, with the outermost last plate partly in section.

Fig. 2 is a cross section on the line A—A of Fig. 1.

Fig. 3 is a plan view looking upwards corresponding to Fig. 1 with one of the last 70 plates turned through an angle preparatory to being removed.

Fig. 4 is a plan view of a single last plate showing more clearly the recess and slot in it for the head of the bolt which 75 constitutes the securing means for the last plates.

Referring to the drawings, the improved last comprises a number of last plates 1 and a base which consists of a miniature 80 foot 2 mounted on or cast integrally with a stem or pillar 3 which is adapted to fit into a hole in a work bench in the usual way. The last plates are curved and otherwise formed to simulate successive sections of a 85 human foot and the number of plates employed depends on the size of the boot, shoe or the like to be repaired. The plates are recessed as at 4 so that each plate interlocks with those above and below it, except 90 the outermost which only interlocks with that below it and the innermost, which interlocks with the foot 2 itself. This interlocking prevents relative movement of the parts in the horizontal plate and to prevent vertical movement of the plates a bolt 95 5 and wing-nut 6 are employed, the nut 6 screwing against a washer 7. The head 8 of the bolt 5 can in one position rest in a recess 9 in and flush with the surface of, 100 the outermost last plate 1 and then holds all the plates securely to the foot 2, but by turning the head or the plate through a right angle it can be made to register with and pass through a slot 10 in the last plate, 105 thus rendering it an easy matter to entirely remove the plate or plates when desired by slackening off the wing nut 6. Fig. 3 shows the outermost last plate turned through an angle preparatory to being removed in this 110 manner.

It is obvious that other modifications

might be made and the form described is only given by way of example.

The drawings show a straight last, but of course it may be made, for finer work, 5 to suit either left or right hand boots or shoes.

I claim:—

A shoemaker's last comprising a base 10 piece, and a plurality of interlocking last plates, each plate being of the outline of a complete foot, said plates being arranged in a series progressively increasing in size 15 away from said base, the plate next adjacent said base being formed to have interlocking engagement therewith, and said base and said plates each being provided with a perforation, the perforations in said plates and said base being in registry in 20 their normal assembled relation, and the perforations in said plates being of the same

size and shape and elongated in form, and said plates each being formed with a recess extending from and communicating with its respective perforation, in combination with a bolt extending through the registering perforations of the assembled plates and base and having an elongated head of such shape and size as to pass through the perforations in said plates when extending lengthwise thereof and to fit in the recess of 25 the outer plate when turned crosswise of the perforation therein, and a nut engaging said bolt and adapted to draw said plates and base firmly together so as to hold them against movement either axially or radially of said bolt.

In witness whereof I have signed this specification.

FREDERICK WILLIAM CHAPPELL.
